UNITED STATES PATENT OFFICE.

EUGENE W. WESTON, OF ALLANDALE, ONTARIO, CANADA.

TOY.

Application filed January 19, 1920. Serial No. 352,473.

To all whom it may concern:

Be it known that I, EUGENE W. WESTON, a citizen of the United States of America, and resident of the town of Allandale, in the Province of Ontario and Dominion of Canada, have invented certain new and useful Improvements in Toys, of which the following is a full, clear, and exact description.

10 This invention relates to improvements in toys and more particularly to toys in the form of aeroplanes or the like.

The object of the invention is to provide a cheap and durable toy which may be folded into comparatively small space for storage or shipment and which may be put into operation in a moment of time.

A further object is to provide an aerial toy which will fly in a predetermined area.

20 A still further object is to provide a toy which may be operated without any motive power other than the force of gravity.

The device consists briefly of a balanced arm carrying at one or both ends miniature reproductions of aeroplanes or other suitable devices. The arm is revolved by means of a fast pitch screw and nut. The particular relative arrangement and construction of the screw, nut and arm may 30 obviously be varied as desired.

In the drawings which illustrate the invention:—

Fig. 1 is an elevation illustrating one form of the device.

35 Fig. 2 is a perspective view illustrating the method of connecting the balanced arm and screw.

Fig. 3 is an elevation of another form of the device.

40 Fig. 4 is a fragmentary plan view illustrating the connection of the screw and nut.

Referring more particularly to the drawings and especially to Figures 1 and 2, 11 designates a fast pitch screw which may 45 be conveniently formed of two wires twisted together, one of the wires being longer than the other and bent over at its ends to form hooks 12. Between the ends of the shorter wire and the hooks, shoulders 13 of any suitable construction may be formed on the longer wire. An arm 14 is provided connected in any suitable way for revolution about the screw 11. One convenient form of connection is to provide a flattened loop 50 15 of wire on the arm 14, which is revoluble about the arm and which embraces between

itself and the arm the screw 11. This loop is flattened in order to prevent relative revolution of the screw and arm except by following the thread of the screw. The loop or nut 15 is preferably located in an offset portion 16 of the arm, one side 17 of which curves from the extremity of the offset to the body portion of the arm, as clearly shown. A toy 18 such as an aeroplane is attached to one extremity of the arm and a counterbalance 19, which may be a simple weight or may be in the form of another toy, possibly similar to the toy 18, is attached to the opposite extremity of the arm. The object of the offset is to dispose the greater part of the arm weight and the weight of the toy and counterbalance below the point of connection between the arm and screw, so that the arm will have no tendency to revolve relatively to the nut, such as would occur if the arm were straight.

In operation the device is suspended by one of the hooks 12 from any suitable support, such as a chandelier or a cord 80 stretched across a room. The arm 14 and devices 18 and 19 carried thereby occupy positions as illustrated in Figure 1. According to the law of gravitation, the arm and the devices 18 and 19 are drawn downwardly or toward the earth. This downward pull is sufficient to cause the nut and arm to follow the pitch of the screw, so that the arm revolves about the screw, until it reaches the lower end and drops from the screw on to the shoulder 13. The nut and arm are now free from the screw and supported by the shoulder 13, so that revolution of the arm due to its own momentum will continue. The screw may now be unhooked from its support at the top and allowed to swing through an angle of 180° around the arm, carrying with it the nut 15. The screw thus inverted may be returned to its support and the operation of 95 the toy will be repeated. When it is desired to ship or store the device, the parts 18 and 19 may be disconnected from the arm 14 and the nut or loop 15 slipped along the curved portion 17 of the offset until the screw 11 is in parallelism with and substantially against the arm proper 14. In this form, the device is very compact and large numbers may be stored or shipped in 100 a small space.

110 While the screw has been described as of twisted wire and the nut as of a wire loop

2
operating in conjunction with the arm, it will be understood that modifications may be made in these structural features without departing from the spirit of the invention, such as for example the use of a twisted flat wire for the screw or the use of a piece of slotted sheet metal hingedly connected to the arm as a nut. Obviously the screw need not be reversible unless desired.

10 In Figures 3 and 4 a slight modification of the device is shown. The screw 21 is supported by a bracket 22 and is provided at one end with a stop 23 having the same relation to the screw as the shoulders 13 have to the screw 11. The opposite end of the screw is rigidly connected to an arm 24, the extremities of which carry a toy 18 and a counterbalance 19. The support 22 is slotted at 25 to receive the screw and forms a nut, compelling revolution of the screw as it works downward. This form of the device is not reversible and, therefore, to facilitate resetting of the toy, the slot 25 is formed with one end open and provided with any suitable form of latch 26, which will normally retain the screw but which will permit the separation of the screw and support for resetting and for storage. The support may be provided with a base 27 adapted in any suitable way for attachment to the wall of a room or other vertical surface.

Obviously, numerous changes of a minor nature may be made in the construction of this form of the device and it must, therefore, be understood that the invention is not limited to the precise details of construction illustrated and described.

The operation of the latter form of the device is very similar to the previous form. The support 22 is suitably located, the latch 26 opened and the screw inserted in the slot 25 adjacent the arm 24. On release, the screw works downwardly through the support, causing the arm to revolve. When the end of the arm is reached, the screw disengages from the slot and the device is supported by the shoulder 23, so that it is free to rotate of its own momentum. To reset, the

screw is removed from the slot 21, raised and reinserted in its first position.

From the foregoing description it will be readily seen that the device may be manufactured very easily and cheaply and may be sold at a low cost. When the device 18 is an aeroplane, it may be provided with a freely revoluble propeller 20 which will be revolved by the movement of the aeroplane through the room. The aeroplane will travel with increasing speed in a descending helix and will eventually travel in a circular path at a fixed elevation until its momentum is gone. The toy is so simple that even very small children can operate the same without assistance and without great danger of destroying the toy. Being of a repeating or reversing construction, the operation is practically continuous and children will not soon tire of playing with it.

Having thus described my invention, what I claim is:—

1. In a toy, a screw, an arm having an offset portion and a nut device receiving the screw therethrough and hingedly connected to the arm offset, whereby the screw may be inserted relatively to the arm.

2. In a toy, a screw comprising a pair of wires twisted together, the end of one wire projecting beyond the end of the other wire and including a shoulder spaced from the other wire sufficiently for the reception of a nut between the shoulder and the end of the other wire, an arm having an offset portion, a nut device carried by the offset portion of said arm and provided with an elongated opening receiving the screw therethrough, and devices mounted at the ends of said arm.

3. In a toy, a screw comprising a pair of wires twisted together, one of said wires having the ends thereof extended beyond the ends of the other wire and provided with shoulders, and an arm provided intermediate of its length with a flat loop embracing the screw and arranged to travel thereon.

In witness whereof, I have hereunto set my hand.

EUGENE W. WESTON.
